UNITED STATES PATENT OFFICE.

HENRI LUGLIEN MARIE JOSEPH BENARD, OF PARIS, FRANCE.

AERIAL SIGNAL LIGHT.

1,413,879.

Specification of Letters Patent. Patented Apr. 18, 1922.

Original application filed May 23, 1919, Serial No. 299,104. Divided and this application filed May 24, 1921. Serial No. 472,260.

To all whom it may concern:

Be it known that I, HENRI LUGLIEN MARIE JOSEPH BENARD, a citizen of the Republic of France, residing at Paris, France, have invented certain new and useful Improvements in Aerial Signal Lights; and I do hereby declare the following to be a full, clear, and exact description of the invention, such as will enable others skilled in the art 10 to which it appertains to make and use the same.

The present invention relates to search lights, particularly adapted for use in aerial navigation, and constitutes a division of application, Serial No. 299,104, filed May 23, 1919, and issued as Patent No. 1,384,659.

An object of this invention is to provide a search light by means of which signal lights may be produced continuously and without 20 interruption in a vertical plane extending from the horizon to the zenith of the search light and wherein the greatest intensity of the light is projected horizontally and owing to the condition of the air, the light may be 25 more readily observed from relatively high altitudes such as at an altitude of 4000 meters.

Another object of the invention is to provide a search light with an aperture or window extending vertically in the upper part 30 of the search light by means of which it is possible to illuminate from the horizon to the zenith of the search light in a continuous manner and with a single source of light.

With the foregoing and other objects in view, the invention will be more fully described hereinafter, and will be more particularly pointed out in the claims appended hereto.

In the drawings, wherein like symbols refer to like or corresponding parts throughout the several views,

Fig. 1 is a vertical section taken longitudinally through a search light constructed according to the present invention; and

Fig. 2 is an end elevation of the same.

Referring to the drawing, the search light, according to the present embodiment, comprises a double ended reflector A which flares toward the opposite ends of the search light 50 for emitting light rays from opposite ends thereof. A single source of light 2, in the present instance an incandescent mantel, is arranged at the focus of the double reflector A, and in the opposite ends of the double reflector A are placed lenses L of suitable con-

struction which are mounted on supports M secured to the sides of the reflector A.

The lenses L, and double reflector A, are arranged so as to project the luminous rays emitted by the source of light 2 into a very intense horizontal beam having a diameter equal to the distance between the top and bottom lines a—b which are horizontal as shown at the top of Fig. 1 by the angle α between a horizontal line a—b and the line c—d which forms a continuation of the parabolic reflecting surface of the member A.

The source of light 2 is also arranged at the focus of the lenses L, and in the center of the portion of the lenses L situated above the horizon of the source of light 2, the lenses L are slotted or interrupted vertically to provide a relatively narrow aperture or window E. Each support M is forked or bifurcated at its upper part to fit the marginal edges of the window E and thus define the window and support the lens.

The upper parts of the reflector A are also slotted in register with the window E, and it will thus be seen that the rays emitted by the source of light passing through this window or interval E give illumination from the horizontal up to the vertical line passing through the axis of the search light. The window E is of the same width in the lenses and in the upper part of the double reflector A so that the pencil of light formed by the direct light rays emitted from the source 2 is of the same horizontal amplitude from the horizon to the zenith. As the horizontal amplitude of the pencil given by the lenses is very small, and the window E being relatively small, the small quantity of the lenses which is removed only inappreciably diminishes the intensity of the beam of the pencil. The graphic illustrations of the direct light rays from the source of light 2 are indicated at R in the drawing and pass uninterruptedly through the windows and the slots formed in the lenses and in the reflector A.

While the present embodiment illustrates the search light of double ended construction, it is of course understood that it may be constructed to operate for emitting light from one end and through the top thereof.

It is obvious that various changes and modifications may be made in the details of construction and design of the above specifically described embodiment of this invention.

tion without departing from the spirit thereof, such changes and modifications being restricted only by the scope of the following claims.

5. What is claimed is:—

1. A signal light for use in aerial navigation comprising a source of light, lenses for projecting the beam from said source of light, and reflectors for reflecting said beam, 10 said lenses and reflectors having apertures therein to allow a narrow beam of direct rays to extend from the horizon to the zenith, substantially as described.

2. A signal light for use in aerial navigation 15 comprising a reflector, a lens mounted in the reflector, a source of light arranged in the reflector at the focus of said lens, and a support carried by the reflector and engaging said lens to maintain the same in position

tion, said lens, support and reflector having 20 registering vertical apertures therein to allow a narrow beam of direct light rays to extend from the horizon to the zenith, substantially as described.

3. In a signal light for use in aerial navigation, a double ended reflector, a lens for each end of the reflector, supports carried in the ends of the reflector and engaging said lenses for maintaining the same in position, a single source of light arranged in the reflector and at the foci of said lenses, said lenses, supports and reflector having registering vertical apertures therein to allow a narrow beam of direct rays to extend from the horizon to the zenith of said source of light, 30 substantially as described.

HENRI LUGLIEN MARIE JOSEPH BENARD.
